ADVERTISING DEVICE

Filed Nov. 4, 1930

UNITED STATES PATENT OFFICE

PAUL H. REGAN, OF FITCHBURG, MASSACHUSETTS

ADVERTISING DEVICE

Application filed November 4, 1930. Serial No. 493,392.

The present invention relates to advertising devices and more particularly to a changeable advertising device.

An object of this invention is to provide a display sign which is so constructed that the frame or body of the sign may be permanently secured in the desired location and the display portion changed when desired.

Another object of this invention is to provide a device of this kind embodying the use of removable inserts or display members which are adapted to be securely held within the frame of the sign without the use of bolts, clips or the like.

A further object of the invention is to provide a device of this kind which is readily and cheaply manufactured.

The above and various other objects and advantages of this invention will in part be described in and in part be understood from the following detail description of the present preferred embodiment, the same being illustrated in the accompanying drawings, wherein:

Figure 1 is a detail front elevation partly cut away of a device constructed according to the preferred embodiment of this invention;

Figure 2 is a vertical sectional view taken on the line 2-2 of Figure 1, and

Figure 3 is an enlarged fragmentary sectional view partly in detail taken on the line 3-3 of Figure 1.

Referring to the drawings wherein like numerals of reference designate corresponding parts throughout the several views, the numeral 10 designates generally a frame comprising an outer frame section 11 and an inner frame section 12. The inner frame section 12 is constructed in the form of a molding having a rabbeted portion 13 whereby to provide a guide along the sides of the inner frame section 12 for receiving an insertible display member 14 in the form of a rectangular sheet of material which may be con-

structed in the form of metal, cardboard, wood or the like. The outer face of the insert 14 is adapted to be painted or the like, and suitable indicia 15 are positioned thereon so as to advertise particular articles which are on sale or display.

The lower end or bottom rail 16 of the frame 12 has its outer face thereof disposed inwardly of the outer face of the side rails 17 and the inwardly extending flange 18 of the inner edge of the side members 17 is outwardly inclined, as at 19, so as to permit the insertion of the display member 14 from the bottom of the frame 12, the guides formed by the flanges 18 being open at the bottom so as to readily permit the insertion of the display card 14 within the frame 12.

When the display member 14 is moved upwardly into the frame 12 and after the lower end thereof has passed or cleared the upper edge of the lower bar 16, the display member 14 at the lower end thereof may be pushed or forced inwardly and permitted to drop down into the rabbet 13, it of course, being understood that the rabbet in the upper rail 20 is of sufficient depth so as to permit the insert 14 to be moved upwardly a sufficient distance to permit the lower edge to clear the upper edge of the bottom rail 16 and when the insert 14 has moved downwardly into the rabbeted portion 13 of the lower rail, the top of the insert 14 will not extend below the lower edge of the top rail 20.

A back 21 is secured to the rear of the frame 12 and if desired, this back 21 at the front face thereof may be provided with suitable advertising indicia 22 which is preferably of a permanent nature and which is visible when the insert 14 has been removed or withdrawn from the frame 12. The lower rail 16 is also provided with a plurality of drain passages 23 and if desired, the rabbeted portion 13 may be suitably inclined, as at 24, so as to permit the rain or melted snow which may enter the frame 12 to drain.

outwardly of the frame through these passages 23.

The outer frame section 11 is provided so as to couple a pair of frames 12 together so that an insertible sign or display member 14 may be positioned at the desired location which will display the desired articles or material on each face thereof. Where only one frame section 12 is used or desired, the outer frame section 11 may be dispensed with.

- 10 1. In the use of this device, the frame sections 11 and 12 may be mounted in the desired location where it is desired to display or advertise certain articles or material and the inner display sheet 21 provided with the suitable 15 indicia of a permanent nature. The insert 14 may be painted a suitable color and the desired indicia 15 positioned thereon so as to advertise or display the articles which it is desired to sell and this insert 14 may then 20 be passed upwardly from the bottom of the frame 12 and slipped into this frame through the slot 19 at the bottom of the frame.

As many of the inserts 14 may be positioned within the frame 12 as it is desired to 25 mount therein and as the capacity of the rabbeted portion 13 will permit. Any rain which may strike the insert 14 and flow downwardly thereon to the bottom of the rail 16 will pass outwardly through the drain 30 openings 23.

It is, of course, understood that various changes and modifications may be made in the details of construction and design of the above specifically described embodiment of 35 this invention without departing from the spirit thereof, such changes and modifications being restricted only by the scope of the following claims.

I claim:

- 40 1. An advertising device of the character described, comprising a frame having a rabbeted inner edge portion constituting a guide, a back secured to the frame, said frame having a bottom member provided 45 with an inwardly offset outer face portion and outwardly and downwardly inclined slots in the side members thereof, and a removable placard positioned in said rabbeted portion.
- 50 2. An advertising device of the character described, comprising a rectangular-shaped frame having rabbeted side, top and bottom members, a back secured to said frame, said bottom member having an outer face inwardly offset from the outer face of said side and top members, said side members adjacent the lower ends thereof having downwardly and outwardly inclined slotted portions communicating with the rabbeted inner edge 55 60 and disposed at each end of the offset face of said bottom member, and an insertible placard adapted to be moved upwardly through said slotted side members whereby to position the placard within the rabbeted portion.

3. An advertising device of the character described, comprising an outer frame, a pair of inner frame members, a fixed placard interposed between said inner frame members, said inner frame members comprising a pair of side frame sections, a top frame section and a bottom frame section, said bottom frame section being inwardly offset from said side frame sections, each of said frame sections having rabbeted inner edge portions, said side frame sections having downwardly and outwardly inclined slotted lower end portions, and a removable placard insertible in said inner frame section through said slotted lower end portions of said side members.

In testimony whereof I hereunto affix my signature.

PAUL H. REGAN.
